UNITED STATES PATENT OFFICE.

PAUL A. RAICHE, OF PROVIDENCE, RHODE ISLAND, ASSIGNOR TO DAVOL RUBBER COMPANY, OF PROVIDENCE, RHODE ISLAND.

PROCESS FOR MAKING AIR PILLOWS AND THE LIKE.

Application filed September 13, 1926. Serial No. 134,951.

This invention relates to certain new and useful improvements in a process for making air pillows and the like and the primary object of the invention is to provide a process which will enable air pillows, air mattresses, and similar air cushioned structures to be made easily and quickly as distinguished from the general practice of making such structure manually.

10 The invention aims to provide a process which enables structures of this kind to be economically produced, at a small cost, and briefly resides in, first, connecting the gussets to the top and bottom of the structures 15 before connecting or sealing the marginal edges of the top and bottom.

The invention has further and other objects which will be later set forth and manifested in the course of the following description:

In the drawings:—

Figure 1 is a top plan view of an air pillow constructed in accordance with the present invention;

25 Figure 2 is a section on line 2—2 of Fig. 1.

Figure 3 is a fragmentary view partly in sections and in perspective showing the first step of the process;

30 Figure 4 is a section on line 4—4 of Fig. 3.

Figure 5 is a perspective view of the mold for sealing the marginal edges of the structure, and

35 Figures 6 and 7 are detail sectional views, showing the manner of connecting the gussets and the marginal sealing respectively.

As shown in Fig. 2 of the drawings, the pillow is composed of an upper member 1 and a lower member 2, each formed of rubberized cloth, the members 1 and 2 forming 40 the opposite side faces of the pillow and being marginally united or sealed as indicated in 3. A series of gussets 4 extend transversely of the pillow and are connected at their top and bottom edges thereto.

45 In the first step of the process, referring to Fig. 3, a mold is employed having a bottom wall 10 and a top wall 11', together with a series of cores or steel cross members 11. The members 11 have reduced ends 12 forming shanks which latter are received in cutouts 13 formed in the mold end walls 14. The cross members 11 are inclined at 14' where same join the shanks 12, and are of a length so that the marginal portions of the

55 tops 1 and 2 will project for a distance beyond the said tapered or bevelled walls 14'. As shown in Fig. 3 of the drawings, the gussets 4 have their top and bottom portions bent over the top and bottom edges of the members 11, and with the parts in this position, pressure, preferably in the presence of heat, is exerted on the press or mold parts so as to unite the gussets to the top and bottom members 1 and 2 of the pillow, as shown particularly in Figs. 2 and 6 of the drawings. 60 The members 11 constitute cores, and upon the gussets being connected to the members 1 and 2 of the pillow, the cores are then removed and the structure is then placed in the press of Fig. 5 of the drawings 65 which latter has a bottom member 20 and a top member 21 with registering openings 22 to receive the usual valve 24 of the pillow. In placing the structure in the press of Fig. 5, the marginal edges of the top and bottom 70 1 and 2 of the pillow are brought together or superimposed and placed between the confronting faces of the members 20 and 21, whereupon pressure is exerted so as to force the marginal edges together and seal same 75 as indicated at 3 in the drawings.

80 It will be understood that the core members 11, after the gussets have been properly united to the top and bottom members 1 and 2, can be easily slid out from between the latter members, since this operation occurs before the members 1 and 2 are marginally united.

85 The invention thus involves the initial securing of the gussets to the pillow faces before marginal union of the latter, which securing is effected by the movable cores 11 and the pressing operation, following which the cores are removed and the marginal edges of the members united.

90 As shown in Figs. 6 and 7 at 4' and 4'' and 2', the joints formed between the parts are beaded, which is effected by control of the heat and pressure so as to form the beads at the joints.

95 Having thus described my invention what I claim as new and desire to secure by Letters Patent is:—

100 1. In an apparatus for making air cushion structures and the like, top and bottom members, end walls for the members, removable cores and means to support the cores from the end walls, said cores having inclined

parts to receive thereover the ends of gusset flanges.

2. In an apparatus of the type set forth for making air pillows having gussets, spaced 5 top and bottom members, end walls having cut-outs therein, and cores arranged in the space between the top and bottom members and having ends of reduced width receivable in the cut-outs, said cores being formed to engage gussets on their opposed side edges, and the reduced ends being formed so as to receive the marginal edges of the gussets and the top and bottom members of the cushion thereover.
- 10 3. In an apparatus for making air pillows having gussets, a top and a bottom member, end walls between the members, cores between said members, and means to removably support the cores from the end walls, 20 the cores being formed to engage gussets on their opposed sides edges, the cores having depressed parts to receive the marginal edges of the gussets and the top and bottom members of the cushion thereover.

4. In an apparatus for making air pillows 25 having gussets, a top and a bottom member, end walls between the members, cores between said members, and means to removably support the cores from the end walls, the cores being formed to engage gussets on 30 their opposed side edges, and with the top and bottom members of the cushion abutting the parts of the gussets that engage said opposed side edges of the cores.

5. In an apparatus for making air cushions 35 having gussets, a top and a bottom member, cores composed of relatively thin plates set-on-edge and disposed between the members, end walls, and means to removably support the cores from the end walls, the cores being 40 formed to receive the gussets over their opposed side edges and with the top and bottom members of the cushion engaged with said parts of the gussets that engage the core side edges. 45

In testimony whereof I have signed my name to this specification.

PAUL A. RAICHE.
